WHEEL FOR A STUMP PULLING MACHINE

Gene A. Ulve, Lake Mills, Iowa, assignor to Tree-Mate
Corporation, Lake Mills, Iowa

Filed Feb. 9, 1973, Ser. No. 331,031

Term of patent 14 years

Int. Cl. D15—03

U.S. Cl. D40—1 E

FIG. 3FIG. 4FIG. 1 is a perspective view of a wheel for a stump pulling machine showing my new design,

FIG. 2 is a side elevational view thereof taken from the line 2—2 of FIG. 1,

FIG. 3 is a side elevational view thereof opposite to that in FIG. 2 and taken from the line 3—3 of FIG. 1, and

FIG. 4 is a perspective view thereof to a reduced scale, and showing the wheel in association with a stump pulling machine, which has been shown in broken lines for illustrative purposes only.

I claim:

The ornamental design for a wheel for a stump pulling machine, as shown and described.
